UNITED STATES PATENT OFFICE.

RICHARD H. HATFIELD, OF NEW YORK, N. Y.

RADIATOR.

1,092,711.

Specification of Letters Patent.

Patented Apr. 7, 1914.

Application filed August 7, 1912. Serial No. 713,920.

To all whom it may concern:

Be it known that I, RICHARD H. HATFIELD, a citizen of the United States, and a resident of the city of New York, borough of Brooklyn, in the county of Kings and State of New York, have invented a new and Improved Radiator, of which the following is a full, clear, and exact description.

My invention relates to an improvement 10 in radiators, preferably of the type designed to remove the heat from the cooling water of the engine of an automobile or other vehicle, and the primary object thereof is to produce a radiator of this type which will be of 15 simple and practical construction, and at the same time operate with the highest possible efficiency for the purpose in view.

Reference is to be had to the accompanying drawings forming a part of this specification, in which the same characters of reference indicate the same parts in all the views.

Figure 1 is a rear elevation of the radiator; Fig. 2 is a horizontal section on the 25 line 2—2 of Fig. 1; Fig. 3 is a plan view of one of the cooling plates through which the radiating tubes pass; Fig. 4 is a perspective view, showing such a plate with one of the radiating tubes passing through it; and Fig. 30 5 is a vertical sectional view on the line 5 of Fig. 1, showing one compartment cut off from the inlet pipe.

My radiator is indicated as a whole by the numeral 1, and it is provided with a 35 hollow top 2 and a hollow bottom 3, the water entering at the top and passing downward through the radiator tubes which connect the hollow top and bottom together, and from the bottom back to the water tank 40 of the engine in the usual way.

The top 2 is provided with a number of compartments 4, separated by longitudinal partitions 5, and the bottom is provided with compartments 6, separated by longitudinal 45 partitions 7. Each of the upper compartments is provided with an inlet opening surrounded by a pipe flange 8, and each of the lower compartments is provided with an outlet opening surrounded by a pipe flange 50 9. The outlet openings at the bottom communicate with a header 10 connected to a conduit 11, and the outlet openings at the top communicate with a similar header or conduit, both headers having flanges to enable them to be bolted to the flanges 8 and 9. In case of damage to one or more pairs of

upper or lower compartments, these headers are disconnected from the corresponding flanges 8 and 9, and a plate 12 having apertures near its circumference to permit the 60 fastening bolts to pass is inserted between the flanges 8 and 9 and the corresponding flanges on the headers, as shown in Fig. 5. When the fastening bolts are again screwed in the particular upper and lower compartments included in the damaged part of the radiator will be cut off entirely. In this way, should a collision or other accident occur which damages part of the radiator, the upper and lower compartments adjacent the 70 damaged portion can be put out of commission. Hence, if one, or even two, of the upper and corresponding lower compartments of the radiator should happen to be out of commission, the third could still be 75 kept in operation and a sufficient cooling effect obtained with this remaining compartment to enable the damaged car to reach the next repair station.

The bottom of the upper part 2, shown at 80 13, and the top of the lower part 3, shown at 14, are connected by a number of radiator tubes 15. The tubes 15 are disposed obliquely, or in lines inclined to the axis of the radiator. This is accomplished by arranging the tubes in alined series, the members of the adjacent series being transversely interspaced. By thus arranging the members of the parallel series, and by forming elongated concave surfaces at the forward sides 85 90 of each tube, provision is made for the delivery of air by each tube and from the concave surface of each tube to the laterally-adjacent tubes and to the pockets formed by the concave surfaces of said adjacent tubes. 95 These tubes are of the shape shown in Fig. 2, and may be described as being triangular in cross-section with transversely concaved sides. They are arranged in sufficient number to conduct the water or other cooling 100 fluid from the top 2 to the bottom 3, and as the sides of these tubes are exposed to the flow of air through the radiator structure between the top 2 and bottom 3, the fluid which passes through these tubes gives up 105 the heat contained therein. The concaved sides of the tubes 15 will permit the expansion of the fluid, and if any of the fluid should freeze in these tubes, with resultant increase in volume which takes place for example when water turns to ice, the bursting 110 of the tubes will be avoided.

Between the top 2 and bottom 3 of the radiator is placed a number of horizontal cooling plates 16. These plates are spaced apart and have openings through which the 5 tubes 15 pass. These openings are formed by making a central aperture 17 from which extend radiating cuts 18, these cuts being approximately 120° apart. Bisecting the portion between each two of these cuts 18 10 are other radiating cuts 19 terminating at their outer ends in apertures 20, and intersected by cross cuts 21 just short of the apertures 20. The portions of the plate 16 on each side of the cuts 19 are then bent, 15 the section between the apertures 20 and the cross cuts 21 forming turned-over lugs 22, and the portion between each cross cut 21 and the adjacent radiating cut 18 forming a turned-over lug 23. This will form a 20 plurality of three-point openings through the plates 16, corresponding in shape to the outer contour of the tubes 15, and the lugs 22 and 23 will engage the sides of the tubes with sufficient firmness to hold the plates in 25 position. These plates will also have lugs 22 and 23 soldered to the sides of the tubes 15, if desired. Each of the pipe flanges 8 and 9 may of course have suitable packing applied to the outer faces of the same when 30 the sections uniting these pipe flanges to the headcrs 10 are secured in position.

The utility and advantage of my radiator will be apparent from the above description. If the automobile should meet with a collision, resulting in damage to one, or even 35 two, of the compartments in the top and bottom, these compartments can be shut off and the third compartment kept in use. This third compartment will cool enough 40 of the water from the jacket of the engine to enable the car to reach a repair point, and thus the danger of having the entire radiator put out of commission by injury to a part thereof will be entirely eliminated. 45 Further, the shape of the tubes 15 will prevent bursting in case any of the water should freeze inside of the same, and the horizontal cooling plate 16 will increase the efficiency of the radiator by conducting heat 50 away from the metal walls of the tubes and thus expose a larger area of metallic surface to the action of the air which blows through the radiator when the car is in motion. The

conductive action of these plates 16 is increased by the lugs 22 and 23, which bring 55 a larger portion of the body of each plate into contact with the outer surfaces of all of the tubes, and the utmost efficiency is thus obtained. Furthermore, the particular method of forming openings through the 60 plate 16 to give passage to the tubes 15 provides a resilient engagement of the plates with the tubes, and this resilient engagement, owing to the frictional surface and bearing of the lugs on the outer surface of 65 the tubes 15, might even be sufficient to hold the plates in position in the radiator under ordinary circumstances. I prefer, however, to solder the plates to the tubes so as to make doubly sure that the plates will at all times 70 retain their proper position with respect to one another.

It will be seen from an inspection of Figs. 2, 3 and 4 that in cross-section the tubes 15 have substantially the shape of a trefoil; 75 that is, this cross-sectional configuration presents three points or corners joined by transversely concaved sides. This three-pointed shape is especially adapted for cooling purposes because of its efficiency in deflecting the air from the sides of the tubes in front against the sides of the tubes located more to the rear of the radiator, and the full cooling action of air which passes through the radiator is thus obtained. 80

Having thus described my invention, I claim as new and desire to secure by Letters Patent:

A radiator, having a plurality of water-circulating tubes arranged in parallel series, 90 said series being disposed in lines perpendicular to the face of the radiator, said tubes having transversely concaved wall sections disposed lengthwise thereof, the tubes of the adjacent series being arranged in staggered 95 relation to pocket and deflect the air passing between said series, for delivery thereof by each tube of one series to the concave sections of the tubes of the adjacent series.

In testimony whereof I have signed my 100 name to this specification in the presence of two subscribing witnesses.

RICHARD H. HATFIELD.
